VENTILATOR CAP

Julius Rosen, Alhambra, Calif., assignor to Angeles Sheet Metal and Plumbing Supply, Los Angeles, Calif., a copartnership

Application July 5, 1955, Serial No. 36,821

Term of patent 14 years

(Cl. D62—3)

FIG. 1.

FIG. 2.

FIG. 3.

FIG. 4.

Fig. 1 is an elevational view of a ventilator cap showing my new design;

Fig. 2 is an elevational view taken at 90° from that of Fig. 1 thereof;

Fig. 3 is a plan view thereof; and

Fig. 4 is a section on line 4—4 of Fig. 2 thereof.

I claim:

The ornamental design for a ventilator cap, substantially as shown.
